UNITED STATES PATENT OFFICE.

HENRY G. DAWSON AND WILLIAM R. DAWSON, OF CHICAGO, ILLINOIS.

DESIGN FOR A FIREPLACE.

SPECIFICATION forming part of Design No. 23,908, dated December 25, 1894.

Application filed November 26, 1894. Serial No. 530,071. Term of patent 7 years.

To all whom it may concern:

Be it known that we, HENRY G. DAWSON and WILLIAM R. DAWSON, citizens of the United States, residing at Chicago, in the county of Cook and State of Illinois, have invented and produced a new and useful Design for Fireplaces, of which the following is a specification, reference being had to the accompanying photograph, showing the complete design.

10 The leading features of our design are a fanciful scroll of leaves, alternating with a raised surface with scalloped border covering the frame of the fire place; a festoon of ribbons and flowers upon the hood; fanciful vegetable forms or stalks, forming the fender, and fret work formed of leaf clusters forming the principal part of the base of the fire place. The entire design is in relief.

15 The frame A, is ornamented with a fanciful scroll comprising alternate sprays of foliage and of raised oval surfaces having scalloped borders and at the middle of the top of the frame is a heart-shaped shield from which the scroll leads in each direction.

20 The hood B, bears upon a chased field three bows of ribbons with streaming ends and a garland hanging in three festoons from the knots of the outer bows and from the streamers of the center bow.

25 The shield C, has its field chased in scallop

form and its lower edge crimped as the edge of a rusle.

The fender D, is in the form of a series of upright bars, each fancifully representing in form, a stalk of vegetable having infolding 35 casings, as corn.

The upper portion e, of the base E, of the fire place is identical in form with the ornamentation of the frame and the lower portion e', is fret work formed of a series of circles 40 united by leaf sprays and each spanned by a cluster of lily leaves.

The outer edge of the frame A, is furnished with a simple form of beading.

We claim as our invention—

45 The design for a fire place substantially as herein shown and described.

In witness whereof we have hereunto affixed our signatures in the presence of two witnesses.

HENRY G. DAWSON.

WILLIAM R. DAWSON.
